(57) **CLAIM**

The ornamental design for the handle of stent placement device, as shown and described.

DESCRIPTION

FIG. 1 is a top perspective view of a handle of stent placement device, showing the new design.

FIG. 2 is a bottom perspective view thereof.

FIG. 3 is a front elevation view thereof.

FIG. 4 is a rear elevation view thereof.

FIG. 5 is a right side elevation view thereof.

FIG. 6 is a left side elevation view thereof.

FIG. 7 is a top plan view thereof; and,

FIG. 8 is a bottom plan view thereof.

The broken lines shown in the drawings illustrate portions of the handle of stent placement device that form the no part of claimed design.
